(57) **CLAIM**

The ornamental design for a cup lid, as shown and described.

DESCRIPTION

FIG. 1 is a perspective view of a cup lid, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the cup lid with a cup and straw; and,

FIG. 10 is a perspective view of the cup lid with a straw, showing that the straw can be placed on the cup lid.

The broken lines shown in the drawings illustrate portions of the cup lid that form no part of the claimed design.

1 Claim, 10 Drawing Sheets
